(57) **CLAIM**

The ornamental design for an applicator refill, as shown and described.

DESCRIPTION

The nature of this product is an applicator refill used in an applicator to apply cleaning and/or disinfecting and/or fragrancing adhesive gel to the inside surface of a toilet bowl. FIG. 1 is a top, front, right side perspective view of an applicator refill embodying our new design; FIG. 2 is a bottom, front, right side elevational view thereof; FIG. 3 is a front elevational view thereof; FIG. 4 is a rear elevational view thereof; FIG. 5 is a right side elevational view thereof, the left side elevational view thereof being a mirror image thereof; FIG. 6 is a top plan view thereof; and, FIG. 7 is a bottom plan view thereof. The broken lines shown in the drawings are for illustrative purposes only and form no part of the claimed design.
